INTERNAL COMBUSTION ENGINE

Filed Aug. 4, 1926

UNITED STATES PATENT OFFICE

ROYAL LEE, OF MILWAUKEE, WISCONSIN, ASSIGNOR TO LEE ENGINEERING RESEARCH CORPORATION, OF MILWAUKEE, WISCONSIN, A CORPORATION OF WISCONSIN

INTERNAL-COMBUSTION ENGINE

Application filed August 4, 1926. Serial No. 127,040.

The invention relates to internal combustion engines, more particularly of the two-stroke-cycle type.

An object of the invention is to provide a two-stroke-cycle engine including charge pre-compression means of a character permitting smooth operation of the engine over a wide range of speed and load.

Another object of the invention is to provide an engine in which a piston forms a by-pass for the pre-compressed charge.

A further object of the invention is to provide an engine in which relatively high base pre-compression can be attained without danger of leakage, thereby affording greater speed and torque range and good fuel economy.

A further object is to provide an engine including by-pass means which will permit variable base pre-compression in accordance with the engine speed and load.

A further object of the invention is to provide an engine including a pressure-responsive inlet valve sensitive in action and quiet in operation.

The invention further consists in the several features hereinafter set forth and more particularly defined in the annexed claims.

In the accompanying drawings, Fig. 1 is a longitudinal sectional elevation of an engine embodying the invention;

Fig. 2 is a transverse sectional view thereof taken on the line 2—2 of Fig. 1;

Fig. 3 is a detail sectional view of the base pre-compression means;

Fig. 4 is a detail plan view of one of the valve seats; and

Fig. 5 is a detail plan view of a disk valve co-operating with the valve seat of Fig. 4.

In these drawings, 10 and 11 indicate a pair of parallel cylinders secured to a crank case 12, there being a plate 13 interposed between the cylinders and the crank case and forming valve seats hereinafter described.

The cylinders 10 and 11 are in communication at their outer ends to form a common combustion chamber 14 into which projects a spark plug 15 or other ignition device, in the case of operation on carbureted or gaseous fuel. The cylinders 10 and 11 are preferably

divided in a plane midway between them and secured laterally together by bolts 16.

A pair of pistons 17 and 18, mounted for reciprocation in the cylinders 10 and 11, respectively, are connected by a common piston pin 19 extending between their intermediate portions and through slots 20 in the adjacent cylinder walls. A crank shaft 21 is journaled in the crank case 12 and is operatively connected to the piston pin 19 by a connecting rod 22 disposed between the cylinders. The outer end of the connecting rod may project into the slots 20 in the cylinder walls in order to obtain a good bearing on the piston pin. This disposition of the connecting rod in the slots is readily obtained by reason of the lateral assembly of the cylinders, which also avoids the necessity for the usual piston pin plugs in the cylinders.

In accordance with well known practice, the pistons 17 and 18 are movable simultaneously outwardly on a compression stroke and simultaneously inwardly on an explosion or power stroke, at the conclusion of which a pre-compressed charge is admitted into one cylinder and blows through the common combustion chamber into the other cylinder, driving the spent gases before it. In the present instance, the spent gases are exhausted through ports 23 in the cylinder 11, the ports being uncovered by the piston 18 near the end of the explosion stroke.

For effecting pre-compression of the charge, it is convenient to use the pistons 17 and 18 acting on their inward stroke, which in general, is also common practice. The present invention contemplates the improvement of engines, preferably of the general type above described, to the end of securing a better engine operation over a wider range of speed and load.

In the present embodiment of the invention, the crank case 12 is provided with a pair of shallow recesses 24 in axial alignment with the cylinders 10 and 11 and connected by a manifold 25 to a carburetor 26 including a throttle valve 26'. The carburetor is provided in case of operation on carbureted fuel, although the invention is not limited to such operation, as the fuel may be introduced by injection into the cylinders and only air sup-

plied to the recesses 24. The recesses 24 are closed at their upper sides by the plate 13, which is provided above each recess with sets of concentric arcuate openings or ports 27 similar to those seen in the valve seat of Fig. 4 hereinafter described. The upper surface of the plate 13 is provided with annular grooves 28 in alignment with the arcuate openings 27 and annular grooves 29 between the sets of arcuate openings, both sets of annular grooves serving to increase the effective area of the openings 27. The disposition of these grooves is similar to that shown in the valve seat of Fig. 4 hereinafter described. The upper surface of the plate 13 is ground to receive a pair of light disk valves 30 of thin metal, one above each recess 24. Each disk valve 30 is provided with annular sets of arcuate openings 31, which register with the annular grooves 29 formed between the arcuate openings 27 of the plate 13. Each disk valve when seated on the plate effectively closes the openings 27 with respect to pressure above the valve. The disk valves 30 are each confined within a circular counterbore 32 in the lower end of each cylinder 10 and 11, such counterbore serving to properly position the disk valve above the apertured plate 13 and to limit the upward movement or lift 30 of the valve.

The outward or upward movement of the pistons 17 and 18 is utilized to draw carbureted air from the recesses 24 into the lower ends of the cylinders, the disk valves 30 being lifted by the suction produced to permit the carbureted air to flow through the openings 27 in the valve plate 13 and thence through the openings 31 in the valves. Following the explosion or downward stroke of the pistons, it becomes necessary to transfer the charge in the lower ends of the cylinders to the upper ends of the cylinders, and this is accomplished in the present instance by admitting the charge into the hollow interior of the pistons and thence outwardly from the upper end of piston 17. The lower or inner end of each piston 17 or 18 is provided with a valve seat plate 33 secured to the open end of the piston trunk by means of an inwardly flanged threaded piston head 34. Each valve plate 33, as seen in detail in Figs. 3 and 4, includes annular sets of arcuate openings or ports 35. The upper surface of each valve plate is ground and provided with annular grooves 36 in alignment with the arcuate openings 35 and annular grooves 37 between the sets of arcuate openings, both sets of annular grooves serving to increase the effective area of openings 35. The ground upper surface of each valve plate 33 receives a light disk valve 38 of thin metal, the disk valve being provided with annular sets of arcuate openings 39, which register with the annular grooves 37 formed between the arcuate openings 35 of the valve plate. Each disk

valve 38 when seated on the valve plate 33 effectively closes the openings 35 with respect to pressure above the valve. The valves 38 are each confined for limited movement adjacent the valve seat by means of an annular spacing ring 40 interposed between the valve seat and the edge of the piston trunk.

The upper or outer end of piston 17 is provided with an apertured valve seat plate 41 which may be identical with the valve seat plate 33 and is secured to the end of the piston trunk by means of an inwardly flanged piston head 42. An apertured disk valve 43, which may be identical with the disk valve 38, is adapted to seat on the valve plate 41 and is confined for limited movement by an annular spacing ring 44 which permits the valve disk to open outwardly or upwardly when the pressure within the piston is greater than the pressure above the piston. The pistons 17 and 18 are placed in communication by the piston pin 19 which is hollow and is provided with ports 45 near its ends registering with similar ports 46 in the pistons. Packing rings 47 are preferably fitted into the piston pin on either side of the ports 45 in order to avoid leakage from the space within the pistons.

In operation, the simultaneous outward or upward movement of the pistons 17 and 18 creates a partial vacuum in the lower ends of the cylinders which causes the disk valves 30 to lift and admit carbureted air from the recesses 24 through the openings 27 of the plate 13, and thence through the openings 31 of the valves. During this travel of the pistons the disk valves 38 in the lower ends of the pistons seat against their respective valve plates 33 to close the openings or ports 35 therein. As soon as the pistons commence their simultaneous inward or downward stroke, the disk valves 30 immediately drop into seating engagement with the plate 13 permitting compression of the trapped charge in the lower ends of the cylinders. When the pressure of the trapped charge exceeds the pressure within the pistons, the disk valves 38 in the lower ends of the pistons are caused to open, thereby forcing the charge into the piston interior as the pistons move downwardly. The clearance at the lower ends of the pistons is made as small as possible in order to obtain good volumetric efficiency and relatively high pre-compression. When the pressure of the charge within the pistons exceeds that in the upper ends of the cylinders, the disk valve 43 in the upper end of the piston 17 is forced open and the compressed charge within the pistons thereupon blows through the openings in the valve plate and disk valve 43 and passes upwardly into cylinder 10, across the combustion chamber 14 and downwardly into the upper end of cylinder 11. The charge forced into the upper end of the cylinders is then compressed

on the subsequent upward travel of the pistons, since the disk valve 43 at the upper end of piston 17 closes as soon as the pressure thereabove exceeds the pressure in the interior of the piston. Simultaneously, a new charge is drawn in at the lower ends of the cylinders in the manner above described. When the pistons reach the upper ends of their travel ignition takes place and the explosion of the charge causes the downward travel of the pistons on their working stroke. When the piston 18 approaches its lowermost position, it uncovers the exhaust ports 23 thereby permitting the spent gases to escape. 10 As soon as the pressure of the remaining spent gases in the cylinders drops below the pressure of the fresh charge accumulated in the pistons 17 and 18 the inlet disk valve 43 opens and the pre-compressed charge which is under considerable pressure blows upwardly in the cylinder 10, through the common combustion chamber 14 and downwardly into the upper end of the cylinder 11, driving the spent gases before it forcing them out of the exhaust ports 23. The disk valve 43 is cooled to a safe temperature by the passage of the pre-compressed charge through it. 20

In previous types of engines employing base or crank case compression, it has been customary to conduct the pre-compressed charge to the combustion chamber by means of a by-pass including ports in the cylinder walls uncovered by the piston in its travel. 30 With such types of engines it has been found impossible to employ a high degree of pre-compression because of excessive leakage of the charge around the piston and through the exhaust ports or slots in the cylinder walls, or both, as the case may be. This condition exists even with a properly fitted piston and is aggravated after the piston has become worn in service. By eliminating the usual piston-controlled by-pass ports in the cylinder walls, it is possible to employ a relatively high degree of charge pre-compression, since there is no danger of charge leakage above noted. The relatively high charge pre-compression is accomplished in the device of the 40 present invention by supplying a minimum clearance space for the pistons on their pre-compression stroke.

The amount of charge pre-compression is variable according to the engine speed and load, this being accomplished since the valve means controlling the pre-compression are pressure-responsive rather than being controlled directly or indirectly by piston position. At small throttle openings of the carburetor the charge which accumulates in the piston space is under somewhat less pressure than at full throttle openings, thus permitting satisfactory operation at low speeds and under light loads. With large throttle openings the pressure of the charge accumulating

within the pistons reaches relatively high values, thereby permitting operation at high speeds with sustained torque because of the rapid scavenging and full charging afforded.

The valve disks of the several valves are 70 sensitive in action, as they are light and are not spring loaded. The short lift of these valves and their seating over a wide area results in quiet operation and does not impair the effective valve area, which is relatively 75 large. Valves of this character can also be successfully applied to engines of the four-cycle type, replacing the spring-loaded suction-operated inlet valves which have heretofore been proposed for this service, but which have not been found altogether suitable, as they do not afford satisfactory operation at low speeds and light loads. 80

The pre-compressed charge issuing from the piston head forms a scavenging column 85 occupying the entire diameter of the cylinder and pushing the spent gases bodily before it, thereby minimizing dilution and providing good scavenging.

Under conditions of light load where the 90 pre-compressed charge entering the cylinders does not reach the volume attained under normal load conditions, the same action occurs as to cylinder 10 and any spent gases then remaining are confined to cylinder 11 95 and part of the combustion chamber 14, which preferably extends above the spark plug points to accommodate the major portion of the compressed charge. The spark plug 15, however, occupies a position over the cylinder 10 so that ignition takes place in an undiluted portion of the charge, even when the amount of charge admitted to the cylinder is relatively small. 100

In order to retain the piston heads on the 105 piston trunks against relative rotation each piston head is provided with an annular groove 34^a receiving therein a resilient ring 34^b carrying an inwardly projecting locking pin 34^c, which extends through the piston head and into the piston trunk, as seen in Fig. 3.

What I claim as new and desire to secure by Letters Patent is:

1. In an internal combustion engine, the 115 combination of a cylinder including a combustion chamber, a piston movable in said cylinder, piston-actuating means extending laterally from said piston, charge pre-compression means including said piston, and charge pressure-responsive valve means at 120 axially spaced portions of said piston permitting a pre-compressed charge to pass into said piston and from said piston into the combustion end of said cylinder. 125

2. In an internal combustion engine, the combination of a pair of cylinders, pistons movable therein, charge pre-compression means including said pistons, and a hollow piston pin connecting said pistons and form- 130

ing a conduit for the pre-compressed charge.

3. In an internal combustion engine, the combination of a pair of cylinders having a common combustion chamber, pistons movable in said cylinders, charge pre-compression means including said pistons, a hollow piston pin connecting said pistons and forming a conduit for the pre-compressed charge, and a pressure-responsive valve in one of said 10 pistons admitting the charge to the combustion chamber of said cylinders.

4. In an internal combustion engine, the combination of a pair of parallel cylinders having adjacent aligned slots, pistons movable in said cylinders, a piston pin connecting said pistons and projecting through said slots, and a connecting rod mounted on said piston pin between said cylinders to swing in a plane normal to the common axial plane 15 of said cylinders and having its opposite ends projecting into said slots for reducing the overhang of said piston pin with respect to said connecting rod.

5. In an internal combustion engine, the combination of a cylinder, a piston movable therein, an apertured valve plate secured to one end of said cylinder, a charge-conducting member secured to said cylinder and having a recess in register with said valve 25 plate, a charge-pressure-responsive disk valve seated on said valve plate within the cylinder and movable off said plate to admit a charge within said cylinder and movable into engagement with said plate to permit 30 pre-compression of the charge by said piston, and by-pass means for conducting the pre-compressed charge to the opposite end of 35 said cylinder.

6. In an internal combustion engine, the combination of a cylinder, a piston movable 40 therein and including an inwardly flanged piston head, an apertured valve plate secured within said piston head, and a charge pressure-responsive disk valve movably seated 45 on said valve plate and having a plurality of ports therein for receiving therethrough a pre-compressed charge.

7. In an internal combustion engine, the combination of a cylinder, a piston movable 50 therein and including a flanged member at its end, an apertured valve plate secured within said flanged member, a charge pressure-responsive disk valve movably seated on said valve plate and having a plurality of ports 55 therein receiving therethrough a compressed charge, and an annular spacing ring disposed about said disk valve to provide lift clearance for said valve.

8. In an internal combustion engine, the combination of a cylinder, a piston movable 60 therein, a piston head having a threaded connection with said piston and having an annular groove, a resilient ring disposed in 65 said groove, and a locking pin engaging said

piston and piston head and retained against withdrawal by said resilient ring.

9. In an internal combustion engine, the combination of a cylinder, a piston movable therein, a piston head having a threaded connection with said piston and having an annular groove, a resilient ring disposed in 70 said groove and having an inwardly projecting member passing through said piston head and into said piston to retain said piston and piston head against relative rotation. 75

10. In an internal combustion engine, the combination of a cylinder, a piston movable therein, and a disk inlet valve on said piston having an area only slightly smaller than the 80 cylinder area and presenting a relatively large effective port area for admitting to said cylinder a scavenging charge occupying substantially the entire diameter of said cylinder immediately adjacent the piston. 85

11. In an internal combustion engine, the combination of a cylinder, a piston movable therein, and valve means having a relatively large port area for admitting into said cylinder an axially directed scavenging charge 90 occupying substantially the entire area of the cylinder from the moment of its admission.

12. In an internal combustion engine, the combination of a cylinder having a combustion chamber, a piston movable in said cylinder and having a transverse sleeve portion provided with a port, a hollow piston pin mounted in said sleeve portion and having a peripheral port registering with the port 95 in said sleeve portion to form a passage for the flow of a charge into said piston, and valve means in said piston for admitting the charge into said combustion chamber. 100

13. In an internal combustion engine, the combination of a pair of cylinders having a common combustion chamber, pistons movable in said cylinders and each having a transverse sleeve portion provided with a 105 port, charge pre-compression means, a hollow piston pin mounted in the transverse sleeve portions of said pistons and having ports registering with the ports in said sleeve portions to form a passage for admitting the pre-compressed charge from one piston to the other, and valve means in one of 110 said pistons admitting the charge to said combustion chamber. 115

14. In an internal combustion engine, the combination of a pair of cylinders having a common combustion chamber, pistons movable in said cylinders and each having a transverse sleeve portion provided with a port, charge pre-compression means, a hollow piston pin mounted in the transverse 120 sleeve portions of said pistons to connect said pistons for simultaneous movement and having closed end portions, said piston pin having ports in its periphery registering with the ports in said sleeve portions of the piston. 125 130

- tons to form a passage for admitting the pre-compressed charge from one piston to the other, and valve means in one of said pistons admitting the charge to said combustion chamber.
15. In an internal combustion engine, the combination of a pair of cylinders having a common combustion chamber, pistons movable in said cylinders and each having a transverse sleeve portion provided with a port, charge pre-compression means, a hollow piston pin mounted in the transverse sleeve portions of said pistons and having ports registering with the ports in said sleeve portions to form a passage for admitting the pre-compressed charge from one piston to the other, and valve means in one of said pistons admitting the charge to said combustion chamber.
20. In an internal combustion engine, the combination of a cylinder having a combustion chamber, a piston movable in said cylinder, a piston head mounted on said piston and having an inturned annular flange, a ported valve plate mounted between said inturned flange and the end of the piston and forming a valve seat on one face, an annular spacing ring also interposed between said inturned flange and the end of the piston and bearing against the valve seat surface of said valve plate, and a ported valve disk disposed within said annular ring to be seated on said valve plate and having a limited lift from its seat determined by the thickness of said spacing ring.
25. In an internal combustion engine, the combination, with a crank case, of a pair of cylinder blocks secured to said crank case and each having a cylinder bore therein forming part of a combustion space at one end of the block opening laterally at the end of the block, attaching bolts securing said cylinder blocks in lateral engagement with the laterally opening ends of said combustion spaces in registering relation to form a common combustion chamber for said cylinders, and a pair of pistons mounted in said respective cylinder blocks and connected for simultaneous movement.
30. In an internal combustion engine, the combination of a cylinder including a combustion chamber, a hollow trunk piston movable therein, a connecting rod exterior to said cylinder, a piston pin having an operative connection with said connecting rod and mounted in an intermediate portion of the piston, charge pre-compression means, and charge-pressure-responsive valve means disposed at opposite end portions of said piston for admitting a pre-compressed charge into said piston and releasing said charge into said combustion chamber from the other end of said piston.
35. In an internal combustion engine, the combination of a cylinder, a piston therein, said cylinder and piston being arranged for relative movement, and a hollow support for said piston extending laterally therefrom and forming a conduit for admitting a charge into said piston.
40. In an internal combustion engine, the combination of a pair of cylinder blocks each having a cylinder bore therein, the cylinder bores in said blocks being arranged in parallel relation, attaching means for separably securing said cylinder blocks laterally together, a pair of pistons mounted in the respective bores of said cylinder blocks, and actuating means for effecting the simultaneous movement of said pistons including a member laterally connecting said pistons.
45. In an internal combustion engine, the combination of a pair of laterally-adjacent cylinders each having a combustion chamber at one end and a pre-compression chamber at the other end, the combustion chambers of said cylinders being in communication to form a common combustion space, a pair of hollow pistons mounted in said respective cylinders to reciprocate therein and each piston forming a reservoir for retaining therein a pre-compressed charge, piston-actuating means connected to intermediate portions of said pistons, valve means for admitting a charge into said pre-compression chambers to be pre-compressed by said pistons, valve means for admitting the pre-compressed charge into both of said pistons and confining said charge within said pistons, and valve means for admitting the charge confined within said pistons into the combustion end of one of said cylinders.
50. In testimony whereof, I affix my signature.
- ROYAL LEE.
55. In an internal combustion engine, the combination of a cylinder having a combustion chamber, a piston movable in said cylinder, a piston head mounted on said piston and having an inturned annular flange, a ported valve plate mounted between said inturned flange and the end of the piston and forming a valve seat on one face, an annular spacing ring also interposed between said inturned flange and the end of the piston and bearing against the valve seat surface of said valve plate, and a ported valve disk disposed within said annular ring to be seated on said valve plate and having a limited lift from its seat determined by the thickness of said spacing ring.
60. In an internal combustion engine, the combination of a cylinder including a combustion chamber, a hollow trunk piston movable therein, a connecting rod exterior to said cylinder, a piston pin having an operative connection with said connecting rod and mounted in an intermediate portion of the piston, charge pre-compression means, and charge-pressure-responsive valve means disposed at opposite end portions of said piston for admitting a pre-compressed charge into said piston and releasing said charge into said combustion chamber from the other end of said piston.
65. In an internal combustion engine, the combination of a cylinder having a combustion chamber, a piston movable in said cylinder, a piston head mounted on said piston and having an inturned annular flange, a ported valve plate mounted between said inturned flange and the end of the piston and forming a valve seat on one face, an annular spacing ring also interposed between said inturned flange and the end of the piston and bearing against the valve seat surface of said valve plate, and a ported valve disk disposed within said annular ring to be seated on said valve plate and having a limited lift from its seat determined by the thickness of said spacing ring.
